STAPLING OR WIRE-STITCHING MACHINE

Arthur H. Maynard, Warwick, R. I., assignor to
 Boston Wire Stitcher Company, Warwick, R. I.,
 a corporation of Maine

Application November 11, 1937, Serial No. 173,982

12 Claims. (Cl. 1-2)

This invention relates to improvements in stapling or wire-stitching machines and more particularly to a heavy duty machine adapted to stitch a lining strip or the like onto the inside face of a metal ring or other annular object.

The machine constituting the subject-matter of the present invention, although adapted for other uses, is designed particularly for stitching fiber strips to the inside face of metal window-frames used in automobile construction. Such annular window-frames must encircle the staple-forming and -driving head to properly position its rim between the head and the clincher-anvil so that the strip may be stitched to the inside face of the frame. In ordinary types of heavy duty stitching machines the heads are too large to permit an annular object to encircle it and the wire-feed usually projects from one side of the head to further prevent its use for the purpose specified. In one well-known type of heavy duty machine the wire is fed horizontally and the staple driven vertically in the same plane. In another well-known type of stitching machine the wire is fed vertically and the formed staple driven in the same direction that the wire is fed. In either case the wire feeding mechanism projects from the head and interferes with the placing of a ring or other annular object to encircle the head.

One object of the present invention is to provide a machine of the type indicated having a compact staple-forming and driving mechanism so arranged as to permit a ring or other hollow article to be stitched while encircling the stapling head.

Another object of the invention is to provide a machine of the type indicated adapted to feed predetermined lengths of a wire strip to be formed into staples and to drive the formed staples in a plane angularly related to the direction of feed of the wire.

Another object of the invention is to provide a machine of the type indicated having a bender-bar which is reciprocated with respect to a forming anvil to form a staple and rotated to position the staple in a plane angularly related to the direction in which the wire is fed.

Another object of the invention is to provide a novel forming anvil for receiving the wire as it is fed and gripping the wire while it is cut and formed into a staple.

Another object of the invention is to provide a machine of the type indicated with a novel form of operating mechanism for actuating the

elements of the staple-forming and -driving mechanism in properly timed relationship.

Still another object of the invention is to provide a machine of the type indicated having its parts of compact and rugged construction to adapt it to attach fiber strips to sheet-metal frames without breakage or abnormal wear of the parts.

Further objects of the improvement are set forth in the following specification which describes a preferred form of construction of the machine, by way of example, as illustrated in the accompanying drawings. In the drawings:

Fig. 1 is a side elevational view in reduced scale of a machine incorporating the novel features of the present invention;

Fig. 2 is an enlarged front elevational view of the upper part of the machine shown with a section of its casing removed to illustrate the relationship of the parts at the beginning of a staple-forming and -driving operation;

Fig. 3 is a top plan view in section through the staple-forming and -driving mechanism showing the parts in the relationship illustrated in Fig. 2 with the anvil overlying the end of the bender-bar;

Fig. 4 is a front elevational view of the stapling head showing the bender-bar reciprocated with respect to the anvil to form a staple;

Fig. 5 is a view similar to Fig. 3 with the parts in the relationship illustrated in Fig. 4 showing the anvil in the guide-slot in the bender-bar;

Fig. 6 is a view similar to Fig. 2 showing the formed staple being driven into the work in a plane angularly related to the direction of wire feed;

Fig. 7 is a view similar to Figs. 3 and 5 with the parts in the relationship illustrated in Fig. 6 showing the forming anvil moved to its outermost position and the bender-bar rotated from the position shown in Fig. 5;

Fig. 8 is a transverse sectional view on line 8-8 of Fig. 2 showing the relationship of the forming anvil and bender-bar before the staple is formed;

Fig. 9 is a transverse sectional view on line 9-9 of Fig. 6 showing the bender-bar rotated through 90° to position a formed staple in a plane angularly related to the direction of feed of the wire;

Fig. 10 is a schematic detailed view showing the gripping means in the anvil held in open or releasing position by the cutting bar;

Fig. 11 is a view similar to Fig. 10 showing the gripper released by the cutter and actuated to engage the wire in the anvil;

Fig. 12 is a transverse sectional view on line 55

12—12 of Fig. 4 showing the camming groove in the periphery of the bender-bar for rotating it during part of its reciprocatory movement;

5 Fig. 13 is a perspective view of the operating elements of the head shown in extended relationship;

Fig. 14 is a perspective view of the bender-bar showing the camming groove on the side opposite from that illustrated in Fig. 13;

10 Fig. 15 is a top plan view showing the staple-forming and -driving head encircled by an annular metal window-frame in position for applying a staple to stitch a fiber strip to the inner face of the frame;

15 Fig. 16 is a view similar to Fig. 15 showing the annular frame turned to another position;

Fig. 17 is a view similar to Figs. 15 and 16 showing the annular frame turned to a third position and illustrating the manner in which 20 the strip is attached to the frame;

Fig. 18 is a perspective view of a section of the window-frame showing the profile of the frame in cross-section and the strip as stitched thereto; and

25 Fig. 19 is a chart showing the relative movement and amplitude of movement of the various parts of the machine during a complete cycle of operation.

The invention is herein shown and described 30 as embodied in a wire-stitching machine having a frame on which the operating elements and driving mechanism are carried and including a feeding means for intermittently advancing predetermined lengths of a continuous strip of wire- 35 stapling material vertically upward to a forming anvil. After a length of wire has been fed a cutting mechanism is actuated which first releases an automatically-operated gripper which cooperates with the forming anvil to grip the wire and 40 thereafter sever an appropriate length thereof from the remainder of the strip. A bender-bar cooperating with the anvil bends the ends of the wire extending from the anvil to form a staple and rotates the formed staple to position it in a 45 plane angularly related to the direction of the wire feed. The formed staple is driven into the work by a driver carried on the bender-bar and actuated independently thereof. The invention also provides a driving mechanism which is so 50 arranged as to operate the feeding means, cutting means, bender-bar and staple-driver in a particular timed relationship to simultaneously form and drive a staple while another length of wire is being fed.

55

Machine frame

Referring to the drawings, the frame of the machine is illustrated in Fig. 1 as comprising a 60 hollow pedestal 2 having a base 3 for supporting it in upright position and a platform 4 at its upper end. Mounted on the platform 4 is a hollow casing 5 of stepped configuration in side elevation comprising a lower section 6, an intermediate section 7 and an upper section or head 8 in which the staple-forming and -driving mechanism is mounted. Although the head 8 is shown in upright position to adapt it to apply the staples horizontally it will be understood that the casing 65 may be arranged to extend laterally to apply the staples in a vertical direction. One side of the lower and intermediate sections 6 and 7 of the casing 5 is closed by a plate 9 while the upper section 8 of the casing is split vertically to form 70 a removable section 10, see Fig. 12, the plate 9

and section 10 being attached to the casing by any suitable means such as bolts or screws.

The upper section 8 of the casing 5 is offset laterally from one side of the casing section 7 as shown in Fig. 2, and mounted on the side of the intermediate sections 7 opposite the end of the section 8 is an upright abutment 11 providing an opening 19 therebetween. The abutment 11 is pivotally mounted at its lower end on the casing section 7 by means of a pin 12 to provide for its adjustment toward and away from the end of the casing section 8. The abutment 11 is adjustable in position by means of a bolt 13 extending therethrough and into the casing section 7, the abutment being held in engagement with the head of the bolt by a spring 14. The upper extended end of the abutment 11 has a centrally-disposed slot 15, shown in Figs. 2 and 3, for mounting an adjustable slide-block 16 having clincher-grooves 17 formed therein. The block 16 is adjustable vertically in the slot 15 and adapted to be clamped in adjusted position by means of a bolt 18. A table 20 is mounted in any desired relationship on the casing 5 by means of struts 21 to support the work to be stitched in proper relationship with respect to the casing section 8 and the clincher-grooves 17 in the block 16.

Although the present machine is adapted for use with other types of work such as rings or other annular objects the table 20 is preferably arranged to support a metal window-frame 25 of the type illustrated in Figs. 15 to 18 and used in automobile construction. Due to the fact that such frames are made of metal the upholstery or trimming cannot be directly tacked thereto and a fiber strip 26 must be attached to its inside face to adapt it to receive tacks or the like. As illustrated in Fig. 18, the window-frame 25 has an annular wall 27 bent to form a flange 28 extending at right-angles thereto with offset portions at the margins thereof. The table 20 is adapted to support the window-frame 25 so that it encircles the upper casing section or head 8 of the machine, see Figs. 15 to 17, with the annular wall 27 positioned in the opening 19 between the end of the casing section 8 and the abutment 11, see Fig. 3.

Driving mechanism

The driving mechanism for the machine comprises a shaft 30 journaled in the casing section 6 with one end projecting beyond the side thereof and its opposite end projecting into the hollow casing section 7. A pulley 31 and clutch-mechanism 32 generally similar to that illustrated and described in my prior United States Letters Patent No. 1,495,342, issued May 27, 1924, is mounted on the outwardly-projecting end of the shaft 30. The pulley 31 is driven by a belt 33 which, in turn, is driven by a motor 34 mounted on a platform 35 supported on the pedestal 2. The pulley 31 is continuously rotated from the motor 34 by the belt 33 and the clutch-mechanism 32 is controlled by a foot-treadle 36 to clutch the pulley to the shaft 30. The treadle 36 is pivoted to the base 3 of the pedestal 2 and connected to a clutch-operating means 37 through a rod 38 and rockable lever 39. Mounted on the opposite end of the shaft 30 in the hollow casing section 7 is a gear 40 and a driving disk 41 having a cam-groove 42 cut in its outer face. A crank-pin 43 projects forwardly from the disk 41 in eccentric relation to the axis of the shaft 30. The gear 40, cam-groove 42 and crank-pin 43 are con- 75

ected to operate the feeding mechanism, the bender-bar and staple-driver, respectively, in the manner as later more fully explained.

Feeding mechanism

- 5 The staples may be formed from a continuous wire strip *W* wound on a spool *50*. The spool *50* is mounted on a suitable spindle *51* supported at the side of the pedestal *2* below the table *20*.
 10 As shown in Figs. 1 and 2, the wire strip *W* is fed vertically upward through a suitable guide *52*, straightening rolls *53*, a one-way clutch *54*, and an extended guide *55* into the upper casing section or head *8*. Between the guide *55* and the one-way clutch *54* are a pair of feed-rolls *56* and *57*. The roll *56* is mounted for angular adjustment on the end of a stub-shaft *58* rotatable in the casing section *7*, while the roll *57* is fast on a stub-shaft *59* journaled in an eccentric sleeve *60* mounted for rotation in the casing section and having a laterally-extending arm *61*. The roll *57* is yieldingly pressed toward the opposite roll *56* by a spring *62* connected between the end of the arm *61* and the casing section *6*,
 15 the spring *62* tending to rotate the eccentric sleeve *60*. Each of the rolls *56* and *57* has a serrated segment *63* of a greater radius than the remainder of the roll for gripping the wire strip when the segments are opposed to each other.
 20 The length of wire fed during one revolution of the rolls *56* and *57* is regulated by adjusting one of the rolls in angular relation with respect to the other roll to alter the duration of contact of the serrated segments *63* with the wire strip *W*. The stub-shafts *58* and *59* carry intermeshing gears *64* at their ends opposite from the feed-rolls *56* and *57* and one of the gears *64* is in mesh with an idler gear *65* meshing with the gear *40*, previously mentioned on the shaft *30*, see Fig. 6.
 25 The intermeshing gears *64* are of the same diameter as the gear *40* so that the feed-rolls *56* and *57* are turned through one complete revolution during one revolution of the drive-shaft *30*. The serrated segments *63* on the feed-rolls *56* and *57* are so arranged as to cause the wire to be fed during that portion of the rotation of the drive-shaft *6* indicated in the graph in Fig. 19 as later explained.

Forming anvil and wire gripper

- 30 The strip of wire *W* is advanced by the feeding mechanism to position a predetermined length *w* adjacent an anvil *70* in the upper casing section or head *8*. As illustrated most clearly in Figs. 3 to 7, the anvil *70* projects laterally from the forward end of a lever *71* and is of generally rectangular form with a concaved cam-face *68* at its rearward side. The lever *71* is located in a slot *72* in the removable section *10* of the casing section *8* and pivotally mounted at its rearward end on a pin *73* extending parallel with the direction of the wire feed. The lever *71* is normally pressed into the casing section or head *8* by a leaf-spring *74* fastened to the casing section at *67*. As shown in detail in Fig. 13, the lever *71* has a longitudinal bore *69* with a lateral slot *75* at its end. The anvil *70* also has a slot *76* on its inner face which extends transversely of the slot *75*. In the outermost position of the anvil *70*, as illustrated in Fig. 7, the slot *76* is in alignment with the guide *55* so that the wire is fed through the slot when advanced by the feeding rolls.

A gripper *77* is located in the slot *75* and has a projecting finger *78* adapted to overlie the slot *76* and a plunger *79* which extends longitudinal-

ly in the bore *69*. The gripper *77* is normally pressed outwardly of the slot *75* by means of a spring *80* pocketed in the bore *69* and bearing against the end of the plunger *79*. Movement of the gripper *77* is controlled by a cross-pin *81* projecting from the plunger *79* through a slot *82* in the lever *71*. The gripper *77* is held in retracted or releasing position while the wire strip is being fed by the cutting mechanism next to be explained and when released by the cutting mechanism the finger *78* engages the length of wire *w* in the slot *76*. Thus it will be apparent that the length of wire advanced vertically upward by the feed-rolls *56* and *57* will pass through the slot *76* in the anvil *70* with its end portions projecting from either side thereof and the adjustment of the feed-rolls is such that the length of the projecting end portions will be equal.

Wire-severing mechanism

20 The wire-severing or cutting-off mechanism comprises a pair of relatively movable elements which cooperate to form a shears which, as illustrated in the present drawings, are constituted by the upper flat face *89* at the end of the guide *55* and a movable cutter-blade *90*, see Fig. 2. The guide *55* is preferably formed in two parts which are clamped in position on the side of the casing section *7* by means of a detachable block *92*. The block *92* is attached to the casing section *7* by a bolt *93* and by loosening the bolt the guide *55* may be raised or lowered to align its upper flat face *89* with the movable cutter-blade *90*.

25 As shown in detail in Fig. 13, the movable cutter-blade *90* has its forward face ground off at an angle to provide a cutting edge *94* and intermediate its ends it is provided with a depending transverse tongue *95*. The blade *90* is mounted on a block *96* with its depending tongue *95* seated in a groove *97* in the block. The block *96* is rigidly attached to the end of a cutter-bar *91* by means of screws or the like, the forward end of the bar having a right-angular recess *98* for receiving the block to properly position the cutter-blade *90* for cooperation with the face *89* at the end of the guide *55*. Adjacent its rearward end the inside face of the bar *91* is slotted to provide a recess *99* forming opposite shoulders *100* and *101*. The bar *91* is mounted to slide in a recessed bearing *102* in the removable portion *10* of the casing section *8*, see Fig. 12, and the forward end of the bar together with block *96* and cutter-blade *90* slide in a recessed bearing *103* in the block *92* attached to the side of the frame.

30 The cutter-bar *91* is reciprocated by a lever *105* in timed relation to the operation of the feeding mechanism to sever a length of the wire *w* from the strip *W*. As illustrated in Figs. 2 and 6, the lever *105* is pivotally mounted intermediate its ends on a pin *107* fast in one end of a link *108* to adapt the lever for oscillatory and bodily movement in the casing section *7*. The link *108* is pivotally mounted at its opposite end on a stud *109* extending transversely of the casing section *7*. The lower end of the lever *105* is bifurcated to receive the end of a connecting rod *110* which is connected thereto by a clevis-pin *111*. The opposite end of the connecting rod *110* is connected to the crank-pin *43* projecting from the driving disk *41*. A stud *106* adjacent the upper end of the lever *105* projects laterally therefrom into the slotted recess *99* at the rearward end of the cutter-bar *91*; and during the forward movement of the upper arm of the lever *105* as

35 40 45 50 55 60 65 70 75 80 85 90 95 100 105 110 115 120 125 130 135 140 145 150 155 160 165 170 175 180 185 190 195 200 205 210 215 220 225 230 235 240 245 250 255 260 265 270 275 280 285 290 295 300 305 310 315 320 325 330 335 340 345 350 355 360 365 370 375 380 385 390 395 400 405 410 415 420 425 430 435 440 445 450 455 460 465 470 475 480 485 490 495 500 505 510 515 520 525 530 535 540 545 550 555 560 565 570 575 580 585 590 595 600 605 610 615 620 625 630 635 640 645 650 655 660 665 670 675 680 685 690 695 700 705 710 715 720 725 730 735 740 745 750 755 760 765 770 775 780 785 790 795 800 805 810 815 820 825 830 835 840 845 850 855 860 865 870 875 880 885 890 895 900 905 910 915 920 925 930 935 940 945 950

it is rocked by the crank-pin 43 and connecting rod 110 the stud 106 engages the shoulder 101 on the cutter-bar. Further movement of the lever 105 acts to slide the bar 91 to actuate the block 96 and cutter-blade 80 carried thereby. Movement of the cutter-blade 80 with respect to the guide 55 causes the cutting edge 94 to cooperate with the flat face 89 at the end of the guide to shear the length of wire *w* from the strip 10 W, see Fig. 2.

Prior to the feeding of a length of wire *w* the cutter-bar 91 is moved rearwardly by the engagement of the stud 106 with the shoulder 100 on the bar which is thereafter held in retracted position as illustrated in Fig. 4 by a friction detent 113, see Fig. 12, until the stud moves forwardly again and positively engages the shoulder 101. During the rearward movement of the cutter-bar 91 the rearward end 112 of the cutter-blade 20 80 engages the cross-pin 81 to retract the gripper 77 and finger 78 and hold the latter in released position so that a length of wire *w* may be fed. The detent 113 is in the form of a plunger pocketed in the casing section 8 and resiliently pressed 25 into engagement with the side face of the bar 91 by means of a coil-spring 114, see Fig. 12. During the initial forward movement of the cutter-bar 91 as effected by the engagement of the stud 106 with the shoulder 101 the rearward edge 112 30 of the cutter-blade 80 releases the cross-pin 81. The spring 114 is thus free to operate the plunger 79 of the gripper 77 to engage the finger 78 with the wire *w* to thereby hold it gripped in position in the slot 76 in the anvil 70, as shown by dash 35 lines in Figs. 10 and 11. Further forward movement of the bar 91 causes the length of the wire *w* to be severed from the strip W while it is held gripped in the anvil 70.

40 *Staple-forming and -driving mechanism*

The staple-forming mechanism comprises a bender-bar 120 which is reciprocable with respect to the anvil 70 to bend the ends of the length of wire *w* at right-angles to form a U-shaped staple 45 *s*. The bender-bar 120 is of cylindrical form, being mounted for reciprocation and rotation in a bore 121 in the casing section 8, see Figs. 8 and 9. As illustrated in detail in Figs. 13 and 14, the bender-bar 120 has a longitudinally-extending 50 guide-slot 122 in its periphery of a width substantially equal to the width of the forming anvil 70 with relatively narrow grooves 123 in the side walls of the slot. At its forward end the slot 122 is deepened to form an inclined pocket 124 and the sides of the pocket are recessed to receive 55 hardened steel guide-blocks 125. The guide-blocks 125 are held in place by screws 126 or the like and are provided with grooves which form a continuation of the grooves 123. A helical cam-slot 127 is also formed in the periphery of the bender-bar 120 with straight longitudinally-extending portions 128 and 129 at its ends, the helical portion therebetween being of any desired pitch. Adjacent its rearward end the bender-bar 60 has a transverse slot 130 in its periphery to provide a driving connection for reciprocating the bar in the manner as later more fully explained.

A staple-supporter 131 mounted in the pocket 70 65 124 of the bender-bar 120 is in the form of a lever having a forwardly-projecting toe 132 shaped with an upper inclined face 138 and adapted to project outwardly between the grooves 123 in the guide-slot 122. The staple-supporter 75 131 is pivoted at its rearward end on a pin 133

extending transversely of the pocket 124 in the bender-bar 120, being normally pressed outwardly to project its toe therefrom by a compression spring 134 held in a bore 135 in the bottom wall of the pocket. 5

Fastened in the wall of the casing section 8 is a stud 136, see Fig. 5, having a roller 137 journaled thereon to engage the cam-slot 127 in the bender-bar 120. Thus, as the bender-bar 120 is reciprocated the roller 137 on the stationary 10 stud 136 cooperates with the cam-slot 127 to cause the bender-bar 120 to first move in a straight line, then to rotate from the position shown in Fig. 8 to that shown in Fig. 9, and thereafter to again move in a straight line. During 15 the first straight line movement of the bender-bar 120 the ends of the hardened steel blocks 125 engage the extended ends of the length of wire *w* lying across the anvil 70 to fold them into the grooves 123 to form a staple *s* which is thereafter 20 turned with the bender-bar as the latter is rotated and then moved in a straight line toward the work to be stitched.

As illustrated most clearly in Figs. 2 and 6, the bender-bar 120 is reciprocated by means of 25 a bell-crank lever 140 pivotally mounted on the stud 109, previously mentioned, at one side of the link 108. One arm 141 of the bell-crank lever 140 extends downwardly to overlie the outer face of the drive-disk 41 and carries a follower roller 30 142 at its end which engages the cam-groove 42 on the disk. The opposite arm 143 of the bell-crank lever 140 extends upwardly through a suitable slot in the casing section 8 and has a reduced rounded end 144 which enters the transverse slot 35 130 in the bender-bar. As the lever 140 is oscillated its rounded end 144 rides in the slot 130 to reciprocate the bender-bar 120 while permitting rotation thereof about its axis. The cam-groove 42 in the driving disk 41 is so formed as to 40 cause the bender-bar 120 to be reciprocated in particular timed relation to the other operative elements as indicated diagrammatically in Fig. 19. As explained above, the reciprocation of the bender-bar 120 first acts to form the staple and 45 thereafter turn the staple to position it in a plane angularly related to the direction in which the wire is fed.

The formed staple *s* is driven into the work by means of a driver-bar 150, illustrated most clearly in Fig. 13. The bar 150 is of generally rectangular outline in cross-section with its outer face rounded to correspond to the curvature of the cylindrical bender-bar 120. The bar 150 is adapted to slide in the guide-slot 122 in the bender-bar 50 120, being formed with laterally-extending flanges 151 which engage the grooves 123 in the slot 122. The outer end of the bar 150 is recessed on one side to receive a removable blade 152 of hardened steel and on the opposite side its end is beveled to 55 form a cam-face 153 which functions for a purpose as will later appear. At its rearward end the bar 150 has a transverse groove 154 for connection with the driving mechanism of the machine.

The bar 150 is actuated by a cylindrical driving element 155 having a collar-like flange 156 at one end engaging the slot 154 in the bar 150. The driving element 155 is of the same diameter as the bender-bar 120 to adapt it to reciprocate in the bore 121 in the head 8 and is provided with a 60 forwardly-projecting end 157 of cylindrical form which projects into a suitable bearing bore in the rearward end of the bender-bar. As the driving element 155 is reciprocated with respect to the bender-bar 120 the flange-and-slot connection 70 75 76

156 and 154 causes the driver-bar 150 to be reciprocated while permitting relative rotation of the driver-bar about the axis of the driving element.

The driving element 155 is actuated by the lever 105 and for this purpose has a slot 158 in its rearward end into which the end of the lever projects. A transverse hole 159 in the end of the driving element 155 aligns with a hole 160 in the end of the lever 105 to receive a clevis-pin 161 to connect the driving element with the lever 105. Thus, when the driving disk 41 is rotated the lever 105 is oscillated by the crank-pin 43 and connecting rod 110 which, in turn, reciprocates the driving element 155 and driver-bar 150, the link 108 providing a flexible connection to compensate for the angularity resulting from the translation of oscillatory movement to reciprocatory movement. It will be understood that the cam-groove 42 and crank-pin 43 are so related on the driving disk 41 as to cause the bender-bar 120 to be actuated to form a staple s, turn it angularly to a new position, move it into position to be driven, and thereafter actuate the driver-bar 150 to drive the formed staple. The structure and arrangement of the mechanism of the machine having now been described in detail, the mode of operation of the complete machine is as next explained.

Mode of operation of the machine

30 The machine is prepared for operation by mounting a spool 50 of the wire stapling material W for rotation on the stud 51 and leading the end of the wire upwardly through the straightening rolls 53, clutch 54, feed-rolls 56 and 57, and guide 55. The cycle of operation commences with the parts in the relationship illustrated in Fig. 2 and before a staple s can be driven the machine must be operated once to feed a predetermined length w of the wire. To start the operation of the machine the treadle 36 is depressed whereby its motion is transmitted through the rod 38 and lever 39 to actuate the clutch-operating means 37 to engage the clutch 32 with the driving pulley 31. With the clutch 32 engaged the shaft 30 is driven by the motor 34 through the belt 33 and pulley 31 to rotate the gear 40 and driving disk 41. There being initially no length of wire in the anvil 70, the bender-bar 120 is merely reciprocated as the bell-crank lever 140 is oscillated by the action of the cam-groove 42 on the follower 142. During the forward stroke of the bender-bar 120 the lever 105 is actuated by the crank-pin 43 on the driving disk 41 and the connecting rod 110 to move the driver-bar 150 through its forward stroke. As the driver-bar 150 moves forwardly the beveled face 153 at its forward end engages the cam-face 68 at the rear of the anvil 70 and rocks the lever 71 on its pivot-pin 73 from the position shown in Fig. 3 to that illustrated in Fig. 7. The slot 76 is then aligned with the guide 55 so that the wire strip W as it is advanced by the feed-rolls 56 and 57 will enter the slot. The feed-rolls 56 and 57 are so related on the stub-shafts 58 and 59 that their serrated segments 63 will engage and grip the wire after the anvil 70 has been moved outwardly to advance a blank w of such length that its ends will project equal distances beyond the sides of the anvil.

70 After a length of wire w has been fed to a position across the anvil 70 the lever 105 will have been oscillated by the crank-pin 43 and connecting rod 110 to engage the stud 106 adjacent to its upper end with the shoulder 101 on the cutter-

bar 91. Continued forward movement of the lever 105 will thus move the cutter-bar 91 forwardly to first release the pin 81 depending from the plunger 79 of the gripper 77. The spring 80 will then slide the gripper 77 outwardly of the lever 71, causing the finger 78 to yieldingly grip the length of wire w in the slot 76. Further continued movement of the cutter-bar 91 causes the cutting edge 94 of the blade 90 to slide across the upper flat face 89 of the guide 55 to sever the length of wire in the manner as illustrated in Fig. 2. During the feeding, gripping and severing operations the bender-bar 120 is reciprocated through its forward and rearward strokes by the bell-crank lever 140. After the bender-bar 120 and driver-bar 150 have been moved rearwardly beyond the anvil 70 the spring 74 rocks the lever 71 from the position shown in Fig. 7 to that shown in Fig. 3 so that the projecting ends of the length of wire w overlie the end of the bender-bar 120 in alignment with its grooves 123. When the parts have been returned to their initial position, illustrated in Fig. 2, the clutch-operating mechanism 37 automatically releases the clutch 32 and a suitable brake, not herein shown, 25 stops the machine. The annular window-frame 25 or other article to be stitched is placed on the table 20 so that it encircles the casing section or head 8 as illustrated in Figs. 15 through 17 to 30 position the vertical wall 27 of the frame in the opening 19 between the end of the bender-bar 120 and the abutment 11, see Fig. 2.

When the foot-treadle 36 is again depressed rotation of the driving disk 41 oscillates the bell-crank lever 140 to reciprocate the bender-bar 120. At the beginning of its forward stroke the bender-bar 120 is moved at a comparatively slow rate from the position shown in Figs. 2 and 3 to the position shown in Figs. 4 and 5, due to the slight eccentricity of that portion of the cam-groove 42 engaging the follower roll 142. During the initial forward movement of the bender-bar 120 the roller 137 is in engagement with the straight portion 129 of the cam-slot 127 so that the bender-bar is held against turning. The end portion of the bender-bar 120 at opposite sides of the guide-slot 122 will thus engage the opposite projecting ends of the length of wire w and bend them over to fold them against the opposite sides of the anvil 70 to form a U-shaped staple s. After 45 the staple s has been formed in this manner and while the straight portion 129 of the cam-groove 127 is engaged by the roller 137 the driver-bar 150 is advanced by the lever 105 acting through the driving element 155 to engage its beveled face 153 with the cam-face 68 on the anvil 70 whereby 50 it will cam the anvil out of the guide-slot 122. The formed staple s will then be supported in the bender-bar 120 with its opposite legs in the grooves 123 thereof while the toe 132 of the staple-supporter 131, having been moved beyond the anvil 70 and pressed outwardly by the spring 134, 55 will engage the crossbar of the staple on its upper inclined face 138.

As the forward movement of the bender-bar 120 is continued the curved portion of the cam-groove 127 will be engaged by the roller 137 to cause the bender-bar to be rotated from the position shown in Fig. 8 to that shown in Fig. 9. In other words, the bender-bar 120 will be rotated to position the formed staple s in a plane angularly related to the direction of feed of the wire strip W. The driver-bar 150 carried by the bender-bar 120 is rotated therewith, the flange 156 and slot 154 permitting relative movement between 70 75

the driver-bar and driving element 155; while the slot 138 in the bender-bar 120 permits relative rotation thereof with respect to its operating lever 140. After the bender-bar 120 has been rotated as explained the straight portion 128 of the cam-groove 127 is engaged by the roller 137 to cause the bender-bar to be moved forwardly without further rotation. As the bender-bar 120 continues its forward movement and completes its forward stroke its end engages the fiber strip 26 and presses it against the vertical wall 27 of the window-frame 25. The driver-bar 150 continues to move forwardly after the bender-bar 120 has completed its forward stroke and drives the formed staple 3 outwardly of the bender-bar to cause its legs to pierce through the fiber strip 26 and metal wall 27 of the window-frame 25. During the driving of the staple 3 the staple-supporter 131 is cammed into the slot 122 in the bender-bar 120 against the action of the spring 134 by the engagement of the end of the driver-blade 152 with the inclined face 138 on the toe 132 of the supporter. As the ends of the legs of the staple 3 penetrate the work they engage the clinching grooves 17 in the abutment 16 and are bent over and clinched against the frame. After the staple has been driven and its legs clinched the bender-bar 120 is moved through its return stroke to its initial position illustrated in Fig. 2 by the bell-crank lever 140. It will be understood that while the staple 3 is being formed and driven the cutter-bar 91 and gripper 77 have been withdrawn and the feed-rolls 56 and 57 operated to advance another length of wire *w* to the anvil 70 in the manner as previously explained. The machine thus forms and drives a staple 3 while another length of wire *w* is being fed into position, and is operated to drive and clinch a staple at each depression of the treadle 36. As indicated in Figs. 15 to 17, the window-frame 25 is turned to various positions between staple-driving operations to stitch the fiber strip 26 to the inside face of the frame at a number of points around its periphery. As illustrated in the drawings the curved portion of the cam-slot 127 has a pitch of such degree as to rotate the bender-bar 120 through a 90° arc during each forward stroke. It will be understood, however, that the pitch of the cam-slot may be varied within the scope of the present invention to rotate the bender-bar through any arc from 0° to 180°. Thus the term "plane angularly related to the direction of feed of the wire" as used in the claims is intended to include any angular relationship from 0° to 180°. It will also be understood that the bender-bar 120 may be provided with a multiplicity of cam-grooves of different pitch with retractable studs in the head 8 to adapt the machine for use with different kinds of work to be stitched; or the studs may be so arranged as to be manually or automatically controlled to alter the degree of rotation of the bender-bar when stitching a single piece of work. It will be observed that the present invention provides a stapling machine having staple-forming and driving means compacted within a space of small dimensions to permit it to be encircled by the work to be stapled and of rugged construction to adapt it to drive staples through metal objects. It will further be observed that the invention provides a machine which drives the staples in a plane angularly related to the direction of the wire feed so that the latter will not interfere with the placing of a ring or other annular object to encircle the stitching mechanism.

While I have herein described and illustrated one preferred embodiment of the machine it will be understood that various modifications may be made in the form and arrangement of the elements thereof without departing from the spirit or scope of the invention. Therefore, without limiting myself in this respect, I claim:

1. In a stapling or wire-stitching machine, an anvil having a slot therein, means for feeding a length of wire through the slot in the anvil, 10 means for gripping the wire in the slot, a bender-bar reciprocable with respect to the anvil to bend the end portions of the wire to form a staple, means for rotating the bender-bar to position the formed staple in a plane angularly related to the direction of feed of the wire, and means for driving the formed staple.
2. In a stapling or wire-stitching machine, an anvil, means for intermittently feeding predetermined lengths of a continuous wire strip of the 20 anvil, means for severing the lengths of wire from the strip, means controlled by the severing means and cooperating with the anvil to grip the wire lengths, a bender-bar reciprocable with respect to the anvil to bend the ends of the wire lengths 25 to form staples, means for rotating the bender-bar to position the formed staples in a plane angularly related to the direction of feed of the wire strip, and means carried by the bender-bar for driving the staples.
3. In a stapling or wire-stitching machine, an anvil, means for feeding a length of wire to the anvil, a bender-bar reciprocable at right-angles to the direction of feed of the wire to bend the end portions thereof to form a staple, a staple-supporter on the bender-bar for supporting the formed staple, means for rotating the bender-bar to position the formed staple in a plane at right-angles to the direction of feed of the wire, and means carried by the bender-bar for driving the 40 formed staple.
4. In a stapling or wire-stitching machine, a frame, clincher-means on the frame, an anvil pivotally mounted on the frame, means for feeding a length of wire to the anvil, a bender-bar 45 reciprocable with respect to the anvil to bend the end portions of the wire to form a staple, means for moving the anvil away from the bender-bar after the staple is formed, means for rotating the bender-bar to position the staple in a plane at right-angles to the direction of feed of the wire and opposite the clincher-means, and means carried by the bender-bar for driving the 50 formed staple.
5. In a stapling or wire-stitching machine, a lever pivotally mounted at one end and having an anvil at its opposite end, means for feeding a length of wire to the anvil, means adapted to cooperate with the anvil to grip the length of wire, a bender-bar adapted to cooperate with the anvil 55 to bend the end portions of the wire to form a staple and to thereafter support the staple, means for rocking the lever on its pivot to move the anvil away from the bender-bar, means for rotating the bender-bar to position the formed staple in a plane angularly related with respect to the direction of feed of the wire, and means for driving the staple.
6. In a stapling or wire-stitching machine, a horizontally-disposed table, an abutment extending upwardly through said table and having laterally-extending clincher-grooves on its vertical face, an anvil above the table in spaced relation to the abutment, means below the table for feeding a length of wire vertically through the table 70 75

- to said anvil, a bender-bar movable at right-angles to the direction of feed of the wire and cooperating with the anvil to form a staple, means for rotating the bender-bar to position the staple in a plane angularly related to the direction of feed of the wire with its legs opposite the clincher-grooves in the abutment, and means for driving the formed staple through the work to clinch its legs thereagainst. 5
- 10 7. In a stapling or wire-stitching machine, an anvil, a bender-bar for forming staples on the anvil, said bender-bar having a transverse slot in its periphery, a lever engageable with the slot in the bender-bar for moving the latter longitudinally while permitting rotation thereof, means for rotating the bender-bar, and a staple-driver cooperating with the bender-bar. 10
- 15 8. In a stapling or wire-stitching machine, a head comprising a casing, an anvil in the casing, a bender-bar in said casing having a longitudinally-extending guide-slot in its periphery, said bender-bar cooperating with the anvil to form a staple, means for reciprocating and rotating the bender-bar, a driver-bar mounted 20 for reciprocation in the guide-slot in the bender-bar and having a transverse slot adjacent one end, and a driving element having an annular flange cooperating with the slot in the driver-bar for moving it longitudinally while permitting 25 it to rotate. 25
- 30 9. In a stapling or wire-stitching machine, a head comprising a casing, an anvil in the casing, a cylindrical bender-bar mounted for reciprocation and rotation in said casing and adapted to cooperate with the anvil to form a staple, said bender-bar having a longitudinally-extending guide-slot in its periphery with grooves in the side walls of said slot, a staple-supporter within the guide-slot, means for reciprocating and rotating the bender-bar, a driver-blade mounted 35 for reciprocation in the guide-slot of the bender-bar, and means for actuating the driver-blade in timed relation to the movement of the bender-bar. 40
- 45 10. In a stapling or wire-stitching machine, a head comprising a casing, a lever pivoted to the casing at one end and having an anvil at its opposite end, a gripper movable longitudinally in the anvil, actuating means for resiliently urging the gripper into cooperative relation with the anvil to grip a length of wire, means for feeding a length of wire to the anvil, a laterally-movable cutter-bar for severing the length of wire, said cutter-bar operating to control the actuating means for the gripper to retract the latter while the wire is being fed and to release the gripper 15 while the wire is being severed, a bender-bar reciprocal with respect to the anvil to form a staple, and means for driving the formed staple. 10
11. In a stapling or wire-stitching machine, a head, an anvil mounted on the head for movement transversely thereof, means for feeding a length of wire to the anvil, a reciprocal bender-bar in the head adapted to cooperate with the anvil to bend a length of wire supported thereon to form a staple and thereafter support the 20 formed staple, and means for holding the bender-bar against turning movement during its forward stroke until the staple has been formed and thereafter turning the bender-bar to position the formed staple in a plane angularly related to 25 the direction of feed of the wire. 25
12. In a stapling or wire-stitching machine, a head, an anvil mounted on the head for movement transversely thereof, means for feeding lengths of wire to the anvil, a reciprocal 30 bender-bar having spaced side walls adapted to bend a length of wire on the anvil to form a staple and thereafter support the formed staple therebetween, said bender-bar having a slot in its periphery with straight axially-extending end 35 portions and a helical portion between the straight portions, and means on the head engaging the slot in the bender-bar whereby the latter during its forward stroke is held against turning until a staple has been formed, thereafter turned to position the formed staple in a plane angularly related to the direction of feed 40 of the wire and finally held against turning during the remainder of its stroke. 40

- to said anvil, a bender-bar movable at right-angles to the direction of feed of the wire and cooperating with the anvil to form a staple, means for rotating the bender-bar to position the staple in a plane angularly related to the direction of feed of the wire with its legs opposite the clincher-grooves in the abutment, and means for driving the formed staple through the work to clinch its legs thereagainst. 5
- 10 7. In a stapling or wire-stitching machine, an anvil, a bender-bar for forming staples on the anvil, said bender-bar having a transverse slot in its periphery, a lever engageable with the slot in the bender-bar for moving the latter longitudinally while permitting rotation thereof, means for rotating the bender-bar, and a staple-driver cooperating with the bender-bar. 10
- 15 8. In a stapling or wire-stitching machine, a head comprising a casing, an anvil in the casing, a bender-bar in said casing having a longitudinally-extending guide-slot in its periphery, said bender-bar cooperating with the anvil to form a staple, means for reciprocating and rotating the bender-bar, a driver-bar mounted 20 for reciprocation in the guide-slot in the bender-bar and having a transverse slot adjacent one end, and a driving element having an annular flange cooperating with the slot in the driver-bar for moving it longitudinally while permitting 25 it to rotate. 25
- 30 9. In a stapling or wire-stitching machine, a head comprising a casing, an anvil in the casing, a cylindrical bender-bar mounted for reciprocation and rotation in said casing and adapted to cooperate with the anvil to form a staple, said bender-bar having a longitudinally-extending guide-slot in its periphery with grooves in the side walls of said slot, a staple-supporter within the guide-slot, means for reciprocating and rotating the bender-bar, a driver-blade mounted 35 for reciprocation in the guide-slot of the bender-bar, and means for actuating the driver-blade in timed relation to the movement of the bender-bar. 40
- 45 10. In a stapling or wire-stitching machine, a head comprising a casing, a lever pivoted to the casing at one end and having an anvil at its opposite end, a gripper movable longitudinally in the anvil, actuating means for resiliently urging the gripper into cooperative relation with the anvil to grip a length of wire, means for feeding a length of wire to the anvil, a laterally-movable cutter-bar for severing the length of wire, said cutter-bar operating to control the actuating means for the gripper to retract the latter while the wire is being fed and to release the gripper 15 while the wire is being severed, a bender-bar reciprocal with respect to the anvil to form a staple, and means for driving the formed staple. 10
11. In a stapling or wire-stitching machine, a head, an anvil mounted on the head for movement transversely thereof, means for feeding a length of wire to the anvil, a reciprocal bender-bar in the head adapted to cooperate with the anvil to bend a length of wire supported thereon to form a staple and thereafter support the 20 formed staple, and means for holding the bender-bar against turning movement during its forward stroke until the staple has been formed and thereafter turning the bender-bar to position the formed staple in a plane angularly related to 25 the direction of feed of the wire. 25
12. In a stapling or wire-stitching machine, a head, an anvil mounted on the head for movement transversely thereof, means for feeding lengths of wire to the anvil, a reciprocal 30 bender-bar having spaced side walls adapted to bend a length of wire on the anvil to form a staple and thereafter support the formed staple therebetween, said bender-bar having a slot in its periphery with straight axially-extending end 35 portions and a helical portion between the straight portions, and means on the head engaging the slot in the bender-bar whereby the latter during its forward stroke is held against turning until a staple has been formed, thereafter turned to position the formed staple in a plane angularly related to the direction of feed 40 of the wire and finally held against turning during the remainder of its stroke. 40
